OPEN MESH TEXTILE FABRIC OR SIMILAR ARTICLE

Max Sadinoff, New York, N. Y.

Application February 17, 1956, Serial No. 40,197

Term of patent 3½ years

(Cl. D92—1)

The figure is a plan view of an open mesh textile fabric or similar article embodying my new design.

I claim:

The ornamental design for an open mesh textile fabric or similar article, substantially as shown.
